UNITED STATES PATENT OFFICE.

BENJAMIN F. WOODRUFF, OF BLUE DIAMOND, KENTUCKY, ASSIGNOR OF ONE-HALF
TO WILLIAM J. McHARGUE, OF BLUE DIAMOND, KENTUCKY.

ROUNABOUT.

Application filed November 23, 1925. Serial No. 70,794.

This invention relates to roundabouts, and more particularly to a device of this character adapted for amusement of children.

The principal object of the invention is to provide a portable roundabout which can be easily disassembled, packed for shipment or stored away in a comparatively small space when not in use, and which can be quickly reassembled for operation.

10 Another object of the invention is to provide a roundabout with a removable sectional pan which will serve to catch a child should he fall into the device while it is in operation and thus prevent his being injured by 15 otherwise falling in between the radial arms of the rotating part and the radial brace bars of the circular track.

A further object of the invention is to provide an improved form of roundabout which 20 is of simple, durable and inexpensive construction and one which can be operated at a maximum speed with a minimum amount of effort.

With these and other objects in view, the 25 invention comprises the various novel features of construction, combination and arrangement of parts as will appear herein-after and be shown in the accompanying drawings.

30 Referring to the drawings:

Figure 1 represents a top plan view of my improved form of roundabout.

Figure 2 is an enlarged sectional elevation taken on the line 2-2 of Figure 1,

35 Figure 3 is an enlarged side elevation of a portion of the device, and

Figure 4 is a detail perspective view of one section of the removable pan.

Referring now to the construction of the 40 invention as disclosed by the accompanying drawings, 1 indicates a circular track consisting of a plurality of sections having their ends cut away to provide overlapping portions 2 detachably connected by any suitable means such as screws or bolts 3.

45 4 is a base member from which radially extend brace bars 5, the ends of the latter being detachably connected to the base member and track by bolts or other means 6.

Extending upwardly from the base member 50 is a stud 7 and positioned in a recess in the upper face of the hub or base member circumferentially of the stud is a bearing member 8.

Rotatably mounted on the stud 7 and resting on the bearing member 8 is a hub member 9 from which extends radial arms 10. The inner end of these arms, like the bars 5 are detachably connected to the hub by 55 bolts or other means 11. A cap screw 12 is threaded into the upper end of the stud 7 for a purpose which will presently appear.

Positioned above and in vertical alignment with the track 1 is a circular frame 13 60 consisting of a plurality of sections joined 65 together by bolts or other suitable means 14.

Mounted on the underside of the circular frame 13 at spaced intervals, preferably intermediate the ends of the frame sections, are depending brackets 15 in each of which are journaled the pedal cranks 16 of a traction wheel 17 provided with a rubber tire to afford a maximum amount of traction and thus facilitate speeding of the roundabout with a minimum amount of effort.

70 Saddles or seats 18 are fixed upon the frame 13 above the traction wheels and mounted in advance thereof are upright bars 19 formed with T heads to provide hand-holds.

80 Arranged within the roundabout is a circular pan 20 comprising a plurality of sections corresponding in number to those of the frame 13. Each section embodies a bottom portion 21 adapted to rest on the radial arms 10, and an upright portion 22 provided uppermost with an inwardly extending flange 23 resting against the underside of the circular frame 13. This flange is formed 85 with bayonet slots 24 for the reception of bolts 25 depending from the frame 13, the heads of the bolts serving to hold the flange 23 up against the circular frame. While the bolts 25 serve to hold the upright portions of the pan, the bottom portions are held in place on the radial arms 10 by screws 26 and the inner meeting ends of the latter are held down by means of the cap screw 12. Each 90 95

section of the pan is also formed intermediate of the sides of the upright portion 22 with a vertical slot 27 to receive the inner pedal crank 16 of each traction wheel.

5 From the foregoing, it will be apparent that I have provided a novel construction of roundabout which can be readily disassembled and quickly reassembled, and one in the use of which the liability of becoming 10 injured by the rider falling in between the radial arms and bars while the upper part is going around, is avoided by the aforementioned pan.

While I have described the preferred embodiment of my invention, I desire to have it understood that such changes in construction and method of operation may be resorted to as are within the scope of the appended claims.

20 I claim:

1. A roundabout comprising a circular track, a circular frame arranged for rotation above and in vertical alignment with said track, traction wheels fixed to said circular frame adapted to support said circular frame and travel on said circular track, pedal cranks fixed to said wheels, and a circular pan of a diameter coincident with that of the circular frame fixed to and supported 25 below said circular frame for rotation therewith as a unit.

2. A roundabout comprising a circular track, a circular frame arranged for rotation above and in vertical alignment with said track, traction wheels fixed to said circular frame adapted to support said circular frame and travel on said circular track, pedal cranks fixed to said traction wheels, a hub provided with radially extending 30 supporting arms pivotally mounted centrally of and in a plane immediately above said track, and a circular pan of a diameter coincident with that of the circular frame mounted on said radial supporting arms and 35 attached to said circular frame for rotation therewith as a unit.

3. A roundabout comprising a circular track, a base, a hub member pivoted on said base member, supporting arms extending 40 radially from said hub member, a circular frame arranged for rotation above and in vertical alignment with said track, traction wheels fixed to said frame adapted to support said circular frame and travel on said track, pedal cranks fixed to each wheel, a circular pan having an upstanding wall at 45 its outer circumference arranged centrally within the roundabout on said radial supporting arms, and means for attaching the bottom of the pan to said radial arms and the upstanding wall of the pan to said circular frame for rotation as a unit.

4. A roundabout comprising a circular track, a circular frame arranged to rotate 50 over said track, seats on said circular frame,

traction wheels attached to and supporting said circular frame, pedal means carried by said traction wheels adapted to be actuated by the rider to rotate the circular frame, a circular pan having a diameter coincident 70 with said circular frame, means for detachably supporting said pan from the underside of said circular frame, said pan adapted to catch and prevent the rider from being injured should he fall inwardly of the device while being operated.

5. A knockdown roundabout comprising a circular track embodying a plurality of sections detachably connected, a circular frame of the same diameter as said track arranged 80 for rotation above it and embodying a plurality of sections detachably connected, a seat on each section, a handgrip mounted on each section in front of said seats, a traction wheel fixed to and supporting each 85 section of said circular frame and adapted to travel on said track, and pedal cranks carried by each traction wheel, and a catch pan having an upstanding wall fixed to and suspended from said circular frame for rotation therewith as a unit.

6. A knockdown roundabout comprising a circular track embodying a plurality of sections detachably connected, a circular frame of the same diameter as said track 95 arranged above it and embodying a plurality of sections detachably connected, a seat on each section, a handgrip mounted on each section in front of said seats, a traction wheel fixed to and supporting each section of said circular frame and adapted to travel on said track, pedal cranks carried by each traction wheel, and a circular catch pan with an upstanding outer wall, said pan embodying a plurality of sections, 100 detachably connected together, and means detachably suspending the catch pan from the underside of said circular frame.

7. A knockdown roundabout comprising a circular track embodying a plurality of sections detachably connected, a circular frame of the same diameter as said track, said frame being arranged above the track and embodying a plurality of sections detachably connected, a seat on each frame section, a handgrip on each frame section in advance of the seat, a traction wheel carried by each frame section and adapted to travel on said track, pedal cranks carried by each traction wheel, a circular pan arranged 110 centrally of said circular frame and detachably supported from the underside of said circular frame, said pan embodying a plurality of sections corresponding in number to those in the frame, and means for detachably connecting each of said sections to the adjacent section of the frame.

8. In a device of the character described, the combination with a circular track, a circular frame, traction wheels carried by 115

said circular frame, pedal cranks carried by each traction wheel, radial supporting arms pivotally mounted centrally of said track, of a circular pan mounted on said radial arms and comprising a plurality of sections, each embodying an upstanding wall at its outer edge formed intermediate its ends with

a slot to receive the adjacent pedal crank, and means for detachably connecting each section of the pan to said radial arms and 10 circular frame for rotation therewith.

In testimony whereof I have affixed my signature.

BENJAMIN F. WOODRUFF.
